ABSTRACT

A modular wireless communications platform is provided. The modular wireless communications platform has a modular host unit and a modular remote unit in communication with the modular host unit. The modular host unit and remote unit include a serial radio frequency communicator configured to convert serial digital data into RF sampled data and configured to convert RF sampled data into serial digital data. The modular host unit and remote unit also include an interface coupled to the serial radio frequency communicator and configured to allow transfer of the RF sampled data from the serial radio frequency communicator to a digital to analog radio frequency transceiver module.

Matter enclosed in heavy brackets [ ] appears in the original patent but forms no part of this reissue specification; matter printed in italics indicates the additions made by reissue; a claim printed with strikethrough indicates that the claim was canceled, disclaimed, or held invalid by a prior post-patent action or proceeding.

RELATED APPLICATIONS

This Reissue Application is a reissue of application Ser. No. 15/948,707, filed Apr. 9, 2018, which issued as U.S. Pat. No. 10,554,424.

The present application is a reissue of application Ser. No. 15/848,707, filed Apr. 9, 2018, which issued as U.S. Pat. No. 10,554,424, and which is a continuation of U.S. application Ser. No. 15/444,134 (hereafter the “134 Application”), entitled “MODULAR WIRELESS COMMUNICATIONS PLATFORM,” and filed on Feb. 27, 2017, which is a continuation of U.S. application Ser. No. 13/335,128 (hereafter the “128 Application”), entitled “MODULAR WIRELESS COMMUNICATIONS PLATFORM,” and filed on Dec. 22, 2011, which is a continuation of U.S. patent application Ser. No. 11/627,251 (hereafter the “251 Application”), entitled “MODULAR WIRELESS COMMUNICATIONS PLATFORM,” and filed on Jan. 25, 2007, wherein the contents of the foregoing applications are hereby incorporated herein by reference. The present application hereby claims the benefit of priority of the ’134 Application, ’251 Application, and the ’128 Application.

BACKGROUND

Technology is continually evolving as consumer needs change and new ideas are developed. Nowhere is this more apparent than in the wireless communications industry. Wireless communication technologies have changed drastically over the recent past and have affected many aspects of our daily lives. As new wireless technologies are developed, companies must invest large amounts of time and resources to upgrade all their existing hardware so that it is compatible with the new technology. Often a change in one component of a system requires an update of the entire system.

The infrastructure of a wireless communication system is commonly designed for a specific technology and a specific frequency band. Thus, once a service provider installs a particular infrastructure, a complete overhaul of a system is required to upgrade to a new technology or change to another frequency band. In addition, if a service provider would like to carry multiple frequency bands, the provider generally has to install a different set of hardware for each technology and frequency band carried. Thus, if the service provider carries four frequency bands of service for mobile customers; four different sets of hardware must be installed in each transmission and reception location.

In addition to changes in technology, consumer demand for a particular service may change after a service is installed. For example, access points initially deployed using over-the-air repeaters or simulcast distributed antenna systems, may need to be replaced with full base stations to support the increased consumer demand. This again, will require major overhauls of existing infrastructure. More-

over, these changes occur not infrequently, are costly and are often necessary to keep pace with competitors within the industry.

For the reasons stated above, and for other reasons stated below which will become apparent to those skilled in the art upon reading and understanding the present specification, there is a need in the art for a wireless communications platform that keeps pace with the rapid changes in wireless communications protocols.

10

SUMMARY

The following summary is made by way of example and not by way of limitation. It is merely provided to aid the reader in understanding some of the aspects of the invention.

In one embodiment, a distributed antenna system is provided. The distributed antenna system includes a host unit and a remote unit coupled to the host unit over a communication medium. The host unit includes an interface adapted to communicate RF signals with an Internet Protocol (IP) gateway as IP data; a baseband processor, coupled to the IP gateway, the baseband processor configured to convert between IP data and baseband, digital signals; and a serializer/deserializer, coupled to the baseband processor, the serializer/deserializer configured to convert between baseband, digital data and a serial data stream. The remote unit includes a serializer/deserializer, coupled to the communication medium, the serializer/deserializer configured to convert between the serial data stream and RF sampled data; an RF module, coupled to the serializer/deserializer, the RF module configured to convert between RF sampled data and an RF signal; and an antenna coupled to the RF module.

In another embodiment, another distributed antenna system is provided. This distributed antenna system includes a host unit and a remote unit coupled to the host unit over the communication medium. The host unit includes an RF module configured to communicate with a base station using RF signals configured for communication over an antenna, the RF module configured to convert between the RF signals configured for communication over an antenna and RF sampled data; a serializer/deserializer coupled to the RF module and configured to communicate with a base station using signals corresponding to baseband, digital data, the serializer/deserializer configured to convert between RF sampled data and first serial data and configured to convert between baseband, digital data and second serial data; and a multiplex module coupled to the serializer/deserializer, the multiplex module configured to multiplex the first serial data and the second serial data into a high speed serial data stream and to demultiplex a high speed serial data stream into the first serial data and the second serial data. The remote unit is configured to convert the high speed serial data stream into one or more RF signals.

55

BRIEF DESCRIPTION OF THE DRAWINGS

The present invention can be more easily understood and further advantages and uses thereof more readily apparent, when considered in view of the detailed description and the following figures in which:

FIG. 1 is an illustration of one embodiment of a system using a modular wireless communications platform;

FIG. 2 illustrates a schematic view of one embodiment of a host unit for use in the system of FIG. 1;

FIG. 3 illustrates a schematic view of one embodiment of a remote unit for use in the system of FIG. 1;

60

FIG. 4 illustrates a schematic view of one embodiment of a digital to analog radio frequency transceiver module for use in either the host unit of FIG. 2 or the remote unit of FIG. 3;

FIG. 5 illustrates a schematic view of one embodiment of a serial radio frequency communicator for use in either the host unit of FIG. 2 or the remote unit of FIG. 3;

FIG. 6 illustrates another configuration of the system of FIG. 1;

FIG. 7 illustrates yet another configuration of the system of FIG. 1;

FIG. 8 illustrates one embodiment of a distributed base station system; and

FIG. 9 illustrates another embodiment of a distributed base station system.

In accordance with common practice, the various described features are not drawn to scale but are drawn to emphasize specific features relevant to the present invention. Reference characters denote like elements throughout Figures and text.

DETAILED DESCRIPTION

In the following detailed description, reference is made to the accompanying drawings that form a part hereof, and in which is shown by way of illustration specific illustrative embodiments in which the device may be practiced. These embodiments are described in sufficient detail to enable those skilled in the art to practice the invention, and it is to be understood that other embodiments may be utilized and that logical, mechanical and electrical changes may be made without departing from the spirit and scope of the present invention. The following detailed description is, therefore, not to be taken in a limiting sense.

The present apparatus is a modular wireless platform that enables a system facilitator to easily and inexpensively adapt their wireless system for use with different data transport mechanisms, frequency bands, communication technologies, and intelligence distribution. This modular platform is made up of a reconfigurable host unit and a reconfigurable remote unit designed for use in a system with a central node and a plurality of distributed antennas. The host unit is located near the central node and facilitates transmission/reception of information to/from the remote units which are located remotely with an accompanying antenna. The remote units function to transmit/receive transmissions from the host unit and transmit/receive wireless signals over accompanying antenna to mobile costumers.

Host unit and remote unit have a modular design and defined interfaces that allow components to be removed and installed to adapt to the needs of the service providers. Both host and remote unit are designed around a serial radio frequency (SeRF) communicator and have a defined interface where different varieties of digital to analog radio frequency transceiver (DART) modules can be connected and disconnected. There are many different DART modules, and each DART module is designed for a particular technology and frequency band. Thus, technology and frequency band adjustments can be made by simply replacing the DART module in the host unit or remote unit. Additionally, host unit and remote unit are designed to allow different transport mechanisms between the host unit and remote unit. For example, the same host unit and remote unit that use fiber optic for inter-unit transmission can be adapted to use E Band wireless transmission instead of or concurrently with the fiber optic. Finally, wireless processing functionality can be placed all on a base station near the central node, or the

functionality can be distributed throughout each of the remote units. The flexibility to modify the functionality of each remote unit allows the wireless platform to support centralized base stations and distributed base stations, either separately or concurrently.

FIG. 1 is a block diagram of one embodiment of a system 100 using a modular wireless communications platform. System 100 is a field configurable distributed antenna system (DAS) that provides bidirectional transport of a fixed portion of RF spectrum from an Internet Protocol (IP) gateway 101 to a remote antenna 108. Along with IP gateway 101 and remote antenna 108, system 100 includes a base station 103, a host unit 102, a transport mechanism 104, and a remote unit 106. Host unit 102, a modular host transceiver and remote unit 106, a modular remote radio head, work together to transmit and receive data to/from remote antennas. In this embodiment, host unit 102 provides the interface between a base station 101 a signal transport mechanism 104. Remote unit 106 provides the interface between transport mechanism 104 and a remote antenna 108. In this embodiment, signal transport mechanism 104 is an optical fiber, and host unit 102 sends optical signals through the optical fiber to remote unit 106.

In the transmission direction of transport, base station 103 performs baseband processing on IP data from IP gateway and places the IP data onto a channel. In one embodiment base station 103 is an IEEE 802.16 compliant base station. Optionally, base station 103 may also meet the requirements of WiMax, WiBro, or a similar consortium. In another embodiment, base station 103 is an 800 MHz or 1900 MHz base station. In yet another embodiment, the system is a cellular/PCS system and base station 103 communicates with a base station controller. In still another embodiment, base station 103 communicates with a voice/PSTN gateway. Base station 103 also creates the protocol and modulation type for the channel. Base station 103 then converts the IP packetized data into an analog RF signal for transmission over antenna 108. Base station 103 sends the RF signal to host unit 102. Host unit 102 converts the RF signal for long distance high speed transmission over transport mechanism 104. Host unit 102 sends the signal over transport mechanism 104, and the signal is received by remote unit 106. Remote unit 106 converts the received signal back into an RF signal and transmits the signal over antenna 108 to consumer mobile devices.

FIG. 2 illustrates a schematic diagram of one embodiment of a host unit 102 for use in a modular wireless communications platform. Host unit 102 has a serial radio frequency (SeRF) communicator 202 that is coupled to a digital to analog radio frequency transceiver (DART) interface 204. DART interface 204 has a plurality of DART connectors each of which is configured to receive a pluggable DART module 208. Further, DART connectors are configured to connect DART module 208 to SeRF communicator 202. DART interface 204 is a common interface that is configured to allow communication between SeRF communicator 202 and different varieties of DART modules 208. Additionally, DART interface 204 allows multiple DART modules 208, 210, 212 to connect to a single SeRF communicator 202. In this embodiment, DART interface 204 is a passive host backplane to which SeRF communicator 202 also connects. In this embodiment, DART interface 204 has eight DART connectors for a DART module 208. In another embodiment, instead of being a host backplane, DART interface 204 is integrated with SeRF communicator 202.

DART modules 208, 210, 212 provide bi-directional conversion to/from analog RF signals from/to digital

sampled RF. In one direction of communication, DART module 208 receives an incoming analog RF signal from base station 103 and converts the analog signal to a digital signal for use by SeRF communicator 202. In the other direction DART modules 208, 210, 212 receive digital sampled RF data from SeRF communicator 202 and convert the data to analog RF for use by base station 103.

Each DART module 208, 210, 212 has a common communication interface for communication with SeRF communicator 202, and a RF processing portion that is exclusive to one frequency band and communication technology. Each DART module 208, 210, 212, therefore, converts to/from one analog RF to the digital signal used by SeRF communicator. For example, DART module 208 is designed to transmit 850 MHz cellular transmissions. As another example, DART module 210 transmits 1900 MHz PCS signals. Some of the other options for DART modules 208, 210, 212 include Nextel 800 band, Nextel 900 band, PCS full band, PCS half band, BRS, WiMax, and the European GSM 900, DCS 1800, and UMTS 2100. By allowing different varieties of DART modules 208, 210, 212 to be plugged into DART interface 206, host unit 102 is configurable to any of the above frequency bands and technologies as well as any new technologies or frequency bands that are developed. Host unit 102, once installed, is field configurable to transmit a variety desired by insertion of a different DART module. Additionally, since SeRF communicator 202 is configured to communicate with multiple different DART modules 208, 210, 212, a single host unit 102 can transmit/receive multiple frequency bands or technologies.

SeRF communicator 202 provides bi-directional conversion to/from a SeRF stream from/to a high speed optical serial data stream. In one direction, SeRF communicator 202 receives incoming SeRF streams from DART modules 208, 210, 212 and sends a serial optical data stream over transport mechanism 104 to remote unit 106. In the other direction, SeRF communicator 202 receives an optical serial data stream from a remote unit 106 and provides SeRF streams to DART modules 208, 210, 212. In one embodiment, the SeRF stream between DART module 208 and SeRF communicator is a parallel stream. In another embodiment, SeRF stream is a serial data stream.

SeRF communicator 202 also allows multiple DART modules 208, 210, 212 to operate in parallel. SeRF communicator 202 actively multiplexes the signals from each DART module 208, 210, 212 such that they are sent simultaneously over a single transport mechanism 104. To accomplish this, SeRF communicator 202 presents a clock signal to each DART module 208, 210, 212 to ensure synchronization.

In one embodiment, an optical multiplex module 214 is optically coupled to SeRF communicator 202. Optical multiplex module 214 performs multiplexing/de-multiplexing of an optical serial data stream to/from SeRF communicator 202 over transport mechanism 104. In this embodiment, optical multiplex module 214 performs wavelength division multiplexing.

In another embodiment, transport mechanism 104 is a wireless millimeter wave signal transceiver (e.g. E Band/70 GHz radio). In this embodiment, host unit 102 sends optical signals to the millimeter wave transceiver which converts the optical signals into millimeter waves and transmits the millimeter waves to a similar millimeter wave transceiver connected to remote unit 106. In yet another embodiment, transport mechanism 104 is a microwave radio transceiver. In still another embodiment, transport mechanism 104 is a T1 connection for transmission of IP data.

FIG. 3 is a schematic diagram of one embodiment of a remote unit 106 for use in a modular wireless communications platform. Remote unit 106 has a SeRF communicator 302, a SeRF interface 304, at least one DART interface 306.

5 In this embodiment, DART modules 308, 309, 311, power amplified 310, duplexer/linear amplifier 312, and optical multiplex module 314 are all installed in remote unit 106 which is connected to antenna 108.

SeRF communicator 302 is designed and performs similar 10 to SeRF communicator 202 of host unit 102. Likewise, DART modules 308, 309, 311 have the same features and design options as DART modules 208, 210, 212 of host unit 102. There is a slight difference from host unit 102, however, in the manner in which SeRF communicator 302 and DART 15 modules 308, 309, 311 are connected. In this embodiment of remote unit 106, SeRF communicator 302 has a SeRF interface 304 which is used to link SeRF communicator to SeRF cables 305. SeRF cables 305 are used to allow DART modules 308, 309, 311 to be physically spaced from SeRF 20 communicator 302 and from other DART modules. SeRF cables 305 connect to DART interface 306. DART modules 308 connected to DART interface 306 and communicate with SeRF communicator 302 through DART interface 306 over SeRF cables 305 and through SeRF interface 304. In 25 another embodiment, SeRF interface 304, and SeRF cables 305 are eliminated and DART interface 306 is integrated into SeRF communicator 302.

DART modules 308 perform similar to DART module 208, except the ultimate destination/origination of the signals to/from DART modules 308 is antenna 108 and not base 30 station 101 as in host unit 102. Optical multiplex module 314 also performs similarly to optical multiplex module 214 of host unit 102.

In the transmission direction, once a signal is converted to 35 analog RF by DART module 308, the signal is sent through RF interface 322 (explained below) to power amplifier 310. Power amplifier 310 amplifies the RF signal received from DART module 308 for output through duplexer/linear amplifier 312 to antenna 108. Similar to DART modules 308, 309, 311, power amplifier 310 is designed for a certain 40 frequency band and technology. Power amplifier 310 is, therefore, removable and is plugged into a power amplifier connector on remote unit 106 which is configured to receive power amplifier 310. Power amplifier connector is configured to couple power amplifier to duplexer/linear amplifier 312 and to DART module 308. Power amplifier 310 also has an alarm and control line that is connected to DART 45 interface 306 for communication to SeRF communicator 302.

Once the signal is amplified by power amplifier 310, duplexer/linear amplifier 312 provides duplexing of the 50 signal which is necessary to connect transmit and receive signals to a common antenna. Duplexer/linear amplifier 312 also provides low noise amplification of received signals and 55 rms power detection of incident and reflected RF power in transmission signal. Similar to DART modules 308, 309, 311 and power amplifier 310, duplexer/linear amplifier 312 is frequency band and technology specific, and is removable. Duplexer/linear amplifier 312 plugs into a connector in 60 remote unit 106 configured to receive duplexer/linear amplifier 312. Furthermore, the connector is configured to couple duplexer/linear amplifier 312 to power amplifier 310 and to antenna 108. Duplexer/linear amplifier 312 also has a control and alarm line that is connected to DART interface 320 65 for communication to SeRF communicator 302. In this embodiment, the frequency band and technology allow use of a single power amplifier 310 and duplexer/linear amplifier

318 by both DART module 308 and DART module 309. In this embodiment, a RF interface 322 is placed between power amplifier 310, duplexer/linear amplifier 312 and DART modules 308, 309. RF interface 322 provides RF splitting/combining of the RF transmit and receive signals necessary to allow connection of two DART modules 308, 309 to a single power amplifier 310 and duplexer/linear amplifier 312.

FIG. 4 shows a schematic view of one embodiment of a DART module 400 for use in either host unit 102 or remote unit 106. There are multiple embodiments of DART module 400 as described above, however, the common elements are described hereafter. DART module 400 has an edge connector 402 for connection to a DART interface. DART module 400 has two main signal paths; a transmission path 404 and a reception path 406. For signals received from a SeRF communicator, DART module 400 forms parallel digital RF data from the incoming SeRF stream, if needed, at FPGA 403. In this embodiment, FPGA 403 is a logic device that is programmed to convert serial digital data into RF sampled data and programmed to convert RF sampled data into serial digital data. DART module 400 then converts the digital signal to analog with digital to analog converter (DAC) 408. Transmission path 404 continues as DART module 400 filters, amplifies and up-converts the analog signal for RF transmission with an assortment of filters 410, amplifiers 412, an oscillator 414, and an attenuator 416. The transmission path exits DART module 400 at an SMA connector 420. The signals travel in the opposite direction down reception path 406, where they are converted from analog to digital and sent to a SeRF communicator. First signals are received at SMA connector 420. DART module 400 then amplifies, down-converts, filters the incoming RF signal with a plurality of filters 410, amplifiers 412, oscillators 414, and attenuators 416. DART module 400 then digitizes the signal with analog to digital converter 422. FPGA 403 then forms a SeRF stream and provides the SeRF stream as parallel digital RF sampled data to a SeRF communicator.

FIG. 5 illustrates a schematic view of one embodiment of a SeRF communicator 500 for use in either host unit 102 or remote unit 106. Serial radio frequency communicator 500 has a plurality of optical input/outputs 502, a clock 504, a field programmable gate array (FPGA) 506, a plurality of DART links 508, and a processor 510. In this embodiment, SeRF communicator 500 has eight (8) optical input/outputs 502. Optical input/outputs 502 connect to optical fiber which is used as a transport mechanism, or optical fiber that links SeRF communicator 500 to an optical multiplexer or a millimeter waver or microwave transceiver. Optical input/outputs 502 receive high speed serial data transmission from another SeRF communicator. In addition, optical input/outputs 502 receive Open Base Station Architecture (OBSAI) protocol data from a baseband unit and/or a base station. In one embodiment, to aid in the ability of optical input/outputs 502 to receive multiple data formats, the signals received from optical input/outputs 502 are transmitted at the same frequency which is set to match the OBSAI protocol. Also, OBSAI data is stripped at the data link layer with a 8B/10B encoder to provide a good ones and zeros balance and remove approximately 20 percent of the OBSAID overhead. Finally, 16-bit filler words are used to provide a 24/25ths transport ratio and match a 2.94 GBps transport speed to enable transport of OBSAI or SeRF data. The OBSAI protocol data is explained in more detail below with reference to FIG. 6. Optical input/outputs 206, also conform to the optical small form-factor pluggable multi-

source agreement. Alternatively, any frequency of signal or shape of connector could be used as is known in the art. SeRF communicator 500 has eight (8) optical input/outputs and DART links 508 for 8 separate DART modules which transmit RF sampled data to/from DART modules.

In one embodiment, DART links 508 and corresponding connectors on a DART interface carry 6 slots of digitized RF payload for reading and writing DART FPGA registers from SeRF FGPA 506. Each slot consists of 16 bits: 15 bits of digitized RF and 1 overhead bit used to transfer FPGA register data. The slots are framed in groups of 6 16-bit words, with each slot repeating at the sampling rate of 15.36 M samples per second. A “superframe” of 32 frames encapsulates the data payload and provides synchronization. Thus, in this embodiment DART links 508 are 16-bit parallel data streams. In another embodiment, DART links 508 are serial. FPGA 506 has eight SERDES to serialize and de-serialize each data stream. Thus, there is one SERDES running for each DART link 508 and optical input/output 502. In this embodiment, each SERDES runs at either half rate or full rate and 50% efficiency such that the SERDES offers 6 RF slots of data. In another embodiment, there are half as many SERDES as DART modules. Thus, the SERDES run at full rate, 100% efficiency and offer 12 RF slots of data.

In one direction, SeRF communicator 500 receives incoming SeRF streams over DART links 508 from DART modules, assembles data frames, and sends an outgoing optical serial data stream through optical input/outputs 502. In the other direction, SeRF communicator 500 receives an optical serial data stream from another SeRF communicator at optical input/outputs 502. SeRF communicator 500 then disassembles the frames of the serial data stream, and provides SeRF streams over DART links 508 to DART modules. SeRF communicator 500 also performs splitting and summing for digital simulcast, and provides a user interface for alarm, status, or configuration management. SeRF communicator 500 also provides bi-directional conversion to/from OBSAI protocol data received at optical input/outputs 502 from/to RF sampled data for DART modules. Additionally, SeRF communicator 500 has at least one RJ-45 connector 216 for receiving IP packets. In one embodiment, RJ-45 connector 216 supports Gigabit Ethernet.

Along with being configurable to communicate on different frequency band/sub-bands and with different technologies, host unit 102 and remote unit 106 are configurable to perform more or less of the wireless processing of the RF signal. Host unit 102 and remote unit 106 are configurable into three different functional configurations. The first configuration is illustrated in FIG. 1 and has host unit 101 and remote unit 106 functioning as a range extender for base station 101. In this configuration, backhaul data is transmitted between host unit 102 and remote unit 106. The second configuration is illustrated in FIG. 6, and has fronthaul data transmitted between host unit 102 and remote unit 106. In this configuration remote unit 106 performs the functionality of a base station. The third configuration is illustrated in FIG. 7 and has ‘midhaul’ data transmission between host unit 102 and remote unit 106. In this embodiment, ‘midhaul’ data refers to OBSAI protocol data or similar partially processed wireless signals. Each of the three configurations will now be explained in further detail.

Referring back to FIG. 1, system 100 shows one configuration for connection of host unit 102 and remote unit 106 in which remote unit 106 functions as a range extender. In this option, base station 103 contains all necessary components to convert IP packets received from an Internet gate-

way into an analog bit stream for transmission over antenna **108**. Except for needed amplification, the signal is ready for transmission over antenna **108** once sent by base station **103**. Host device **102** and remote device **106** do not perform any further processing on the data except what is required to send and receive the data over long range transmission. Host unit **102** contains the components as illustrated in FIG. 2 and receives the analog signal from base station **103** at the DART module matching the analog signal frequency band and technology. Host unit **102** converts the signal and transmits the data over transport mechanism **104**. Remote unit **106** contains the components as shown in FIG. 3. Remote unit **106** receives the signal from transport mechanism **104** and sends the data to the DART module matching the frequency band and technology. The signal is then converted and transmitted over antenna **108** to mobile users.

FIG. 6 shows another configuration of a system **100** where base station functionality is performed at remote unit **106**. This configuration provides increased capacity to a network of antennas by allowing each remote unit **106** to function as a base station. In this embodiment of system **100**, IP data is not processed by a base station before sending to remote unit **106**. Instead IP data is received at host unit **102** directly from IP gateway **101**. IP data is received at an RJ-45 connector on SeRF communicator **202** of host unit **102**. In this configuration, therefore, the signal does not travel through DART module **208**, **210**, **212** of host unit **102**. The IP data is converted to a serial optical stream and transmitted over transport mechanism **104** to remote unit **106**. Remote unit **106** receives the IP data at SeRF communicator **302**.

Remote Unit **106**, in this embodiment, has a baseband unit **602** which is connected to a slot of DART interface **306**. In this configuration, baseband unit **602** is in fact a remote WiMax base station which replaces the functionality of base station **103** in the first configuration. SeRF communicator **302** converts the packetized optical data received into 25-75 Mbps data and sends the data over to baseband unit **602**. Baseband unit **602** performs baseband processing to put the IP data onto a channel. Baseband unit **602** also creates the protocol and modulation type for the channel. Baseband unit **602** then converts the data to match the OBSAI protocol. This OBSAI data is sent back into an optical input/output **502** of SeRF communicator **302**. SeRF communicator **302** uses software to convert the OBSAI protocol data into digital RF sampled data and sends the digital RF data to DART module **308** for transmission over antenna **108**. In another embodiment, baseband unit **602** converts IP data to/from common public radio interface (CPRF). Alternatively, any digital baseband protocol, including standard and proprietary protocols, or any software defined radio interface could be used by baseband unit **602** and SeRF communicator **302**.

FIG. 7 illustrates yet another configuration of a system **100** in which remote unit **106** performs the functionality of a base station, and the baseband processing is performed prior to transmission by host unit **102**. In this embodiment, IP data is received at a baseband unit **702** which converts the IP data into data conforming to the OBSAI protocol. In another embodiment, OBSAI protocol data is communicated between SeRF communicator **202** and a base station **103** as shown in FIG. 1. Alternatively, any of the protocols listed with respect to FIG. 6 could be used. The OBSAI protocol data is converted to serial data in SeRF **202** of host unit **102** before the serial data is transmitted to remote unit **106**. Here again, DART module **208** is not used at host unit **102**, since the data has not been converted to RF yet. The OBSAI protocol data is received by remote device **106** at SeRF

communicator **302**. SeRF communicator **302** converts the OBSAI protocol data into digital RF sampled data and interfaces with DART **308**. DART **308** converts the data to analog RF and the signal is sent over antenna **108**.

5 Since host unit **102** and remote unit **106** have multiple input/outputs and can have multiple types of DART modules connected to each, host unit **102** and remote unit **106** are configured to multiplex different functional configurations through different input/outputs simultaneously. Thus, in one 10 embodiment, a first input/output of host unit **102** and remote unit **106** function as a range extender for a base station. A second input/output of host unit **102** and remote unit **106** function to transmit 'midhaul' data. At the same time a third input/output of host unit **102** and remote unit **106** functions 15 to transmit fronthaul data and remote unit **106** performs baseband processing upon the data.

The modular design of modular wireless communications protocol allows many different combinations of transport mechanisms, frequency bands, communication technologies, and processing functionality to operate simultaneously 20 on the same host unit and remote unit.

Placing a base station at a remote wireless communication stations such as described with the configuration of FIG. 6 allows service providers to set up a distributed base station 25 system. FIG. 8 illustrates one embodiment of a distributed base station system **800**. System **800** has a central node **801** having an IP gateway and a plurality of remote wireless communication stations **802**, **804**, **806**, **808**, **810**, **812**. Each remote station **802**, **804**, **806**, **808**, **810**, **812** includes a 30 remote unit **814**, **816**, **818**, **820**, **822**, **824**, an antenna **826**, and a router **828**. In this embodiment, remote unit **818** and remote unit **820** are configured into a WiMax compatible base station. In another embodiment, all remote units **814**, **816**, **818**, **820**, **822**, **824** are configured into PCS cellular 35 base stations. Alternatively, any number of remote units **814**, **816**, **818**, **820**, **822**, **824** could be configured into a base station for any of the technology or frequency bands described with respect to system **100**. Each remote station **802**, **804**, **806**, **808**, **810**, **812** functions similarly, except that 40 they will vary based on the configuration of their respective remote unit **814**, **816**, **818**, **820**, **822**, **824**.

Distributed base station system **800** has many advantages 45 over traditional centralized base station systems. For example, remote stations **806**, **806** which are equipped with a base station do not need to transmit signals back to central node **801** for base station processing. Instead, when an RF signal is received via antenna **826** at remote station **806**, for example, remote station **806** processes the RF signal with remote unit **818**, which is configured as a base station. 50 Processing the RF signal forms a second RF signal which is then routed toward the destination of the RF signal. In this embodiment, the RF signal received at remote unit **806** is from a first mobile device which is in communication with a second mobile device which is the destination of the 55 second RF signal. In another embodiment, the RF signal is received from a fixed internet user and the destination of the second RF signal is on the internet via IP gateway at central node **801**. In this embodiment, the second mobile device is within transmission range of remote station **812**. Thus, after 60 processing by remote unit **818** at remote station **806**, routers **828** at remote stations **806**, **810**, **812** route the second RF signal through remote station **810** to remote station **812**. Thus, distributed base station system **800** simplifies and speeds up the processing of wireless signals.

65 In addition, there are many other advantages of a distributed base station system. For example, since each remote station **802**, **804**, **806**, **808**, **810**, **812** includes a router, a best

11

path is found to the from the origination remote station to the destination remote station. This decreases the latency of communication transmission, and also reduces unnecessary network traffic. In addition, in one embodiment where each remote station 802, 804, 806, 808, 810, 812 is equipped with a base station, each remote station 802, 804, 806, 808, 810, 812 obtains dedicated capacity to the system. Dedicated capacity refers the allocation of an unvarying amount of bandwidth to each remote station 802, 804, 806, 808, 810, 812. For example, in one embodiment, each remote station 802, 804, 806, 808, 810, 812 is allocated 25 Mbps of bandwidth. This is not possible in previous systems, because each remote station shares the capacity of a single central base station.

In one embodiment, remote stations 802, 804, 806, 808, 810, 812 are set up in a ring configuration as shown in FIG. 8. The ring structure is advantageous, because a ring configuration allows multiple paths to be found to each remote station 802, 804, 806, 808, 810, 812. Thus, there are more options for a best path to be found to each remote device 802, 804, 806, 808, 810, 812, and congested areas are more easily avoided. In another embodiment, shown in FIG. 9, remote stations 902, 904, 906, 908, 910, 912 are arranged into tree configurations. Tree configurations are advantageous, because they reduce the complexity of the network and the amount of communication links that must be established. Tree configurations, however, still provide reduced latencies by allowing signals to be routed through the local hubs (e.g. remote station 902 and 908) and not requiring transmission to central hub 901.

In yet another embodiment, a plurality of remote stations is set up in a daisy chain configuration. Alternatively, any combination of ring, tree, or daisy chain configurations could be used to network a plurality of remote stations.

Although specific embodiments have been illustrated and described herein, it will be appreciated by those of ordinary skill in the art that any arrangement, which is calculated to achieve the same purpose, may be substituted for the specific embodiment shown. This application is intended to cover any adaptations or variations of the present invention. Therefore, it is manifestly intended that this invention be limited only by the claims and the equivalents thereof.

What is claimed is:

1. A system, comprising:

a host unit configured to communicate Internet Protocol (IP) data with an IP gateway, wherein the host unit includes:

a baseband processor configured to perform baseband processing to place IP data onto a channel, wherein the baseband processor is configured to convert between IP data and baseband, digital data;

a serial interface configured to convert between baseband, digital data and one or more first serial data streams;

an RF interface configured to convert between RF signals configured for communication over an antenna and RF sampled data, the RF unit interface comprising a first RF module configured to communicate with a base station using a first frequency band and a second RF module configured to communicate with the base station using a second frequency band;

a remote unit, communicatively coupled to the host unit over a communication medium, the remote unit including:

a serial interface, communicatively coupled to the communication medium, the serial interface config-

12

ured to convert between one or more first serial data streams and radio frequency (RF) sampled data; an RF interface, communicatively coupled to the serial interface, the RF interface configured to convert between RF sampled data and one or more RF signals.

2. The system of claim 1, [wherein the host unit further comprises an RF interface configured to convert between RF signals configured for communication over an antenna and RF sampled data,] wherein the serial interface of the host unit is further configured to convert between RF sampled data and one or more second serial data streams, wherein the serial interface of the remote unit is further configured to convert between the one or more second serial data streams and RF sampled data.

[3. The system of claim 2, wherein the RF interface of the host unit includes a first RF module configured to communicate with a base station using a first frequency band and a second RF module configured to communicate with the base station using a second frequency band.]

4. The system of claim 2, wherein the host unit further includes a multiplexer configured to multiplex the one or more first serial data streams and the one or more second serial data streams for concurrent communication over the communication medium; and

wherein the remote unit further includes a demultiplexer configured to demultiplex the one or more first serial data streams and the one or more second serial data streams.

5. The system of claim 1, wherein the serial interface of the host unit is further configured to convert between IP data and one or more second serial data streams;

wherein the serial interface of the remote unit is further configured to convert between the one or more second serial data streams and IP data;

wherein the remote unit further includes a second baseband processor, communicatively coupled to the serial interface of the remote unit, wherein the second baseband processor is configured to perform baseband processing to place IP data onto a channel, wherein the second baseband processor is configured to convert between IP data and baseband, digital data;

wherein the serial interface of the remote unit is configured to convert between baseband, digital data and RF sampled data.

6. The system of claim 1, wherein the baseband, digital data corresponds to open base station architecture (OBSAI) protocol data or common public radio interface (CPRI) protocol data.

7. The system of claim 1, wherein the host unit further comprises an interface configured to communicate baseband, digital data with a base station.

8. A host unit comprising:
a baseband processor configured to communicate Internet Protocol (IP) data with an IP gateway, wherein the baseband processor is configured to perform baseband processing to place IP data onto a channel, wherein the baseband processor is configured to convert between IP data and baseband, digital data; and
a serial interface configured to convert between baseband, digital data and one or more first serial data streams and communicate the one or more first serial data streams with a communication medium, wherein the serial interface is configured to convert between IP data and one or more second serial data streams and communicate the one or more second serial data streams with the communication medium.

9. The host unit of claim 8, further comprising a radio frequency (RF) interface configured to convert between RF signals configured for communication over an antenna and RF sampled data, wherein the serial interface is configured to convert between RF sampled data and one or more second serial data streams and communicate the one or more second serial data streams with the communication medium.

10. The host unit of claim 9, wherein the RF interface includes a first RF module configured to communicate with a base station using a first frequency band and a second RF module configured to communicate with the base station using a second frequency band.

11. The host unit of claim 9, further comprising a multiplexer/demultiplexer configured to multiplex/demultiplex the one or more first serial data streams and the one or more second serial data streams.

12. The host unit of claim 8, wherein the serial interface is configured to convert between IP data and one or more second serial data streams and communicate the one or more second serial data streams with the communication medium.]

13. The host unit of claim 8, wherein the baseband, digital data corresponds to open base station architecture (OBSAI) protocol data or common public radio interface (CPRI) protocol data.

14. The host unit of claim 8, further comprising an interface configured to communicate baseband, digital data with a base station.

15. A remote unit, comprising:

a radio frequency (RF) interface configured to communicate radio frequency (RF) signals with an antenna and convert between RF signals and RF sampled data; a serial interface configured to convert between RF sampled data and baseband, digital data; a baseband processor configured to convert between baseband, digital data and Internet Protocol (IP) data; wherein the serial interface is configured to convert between IP data and one or more first serial data streams and communicate the one or more first serial data streams with a communication medium.

16. The remote unit of claim 15, wherein the RF interface includes a first RF module configured to communicate with the antenna using a first frequency band and a second RF module configured to communicate with the antenna using a second frequency band.

17. The remote unit of claim 15, wherein the serial interface is further configured to convert between sampled RF data and one or more second serial data streams, wherein the serial interface is further configured to communicate the one or more second serial data streams with the communication medium.

18. The remote unit of claim 17, further comprising a multiplexer/demultiplexer configured to multiplex/demultiplex the one or more first serial data streams and the one or more second serial data streams.

19. The remote unit of claim 17, wherein the baseband, digital data corresponds to open base station architecture (OBSAI) protocol data or common public radio interface (CPRI) protocol data.

20. The remote unit of claim 15, wherein the serial interface is further configured to convert between baseband, digital data and one or more second serial data streams and communicate the one or more second serial data streams with the communication medium.

21. A system, comprising:

a host unit configured to receive Internet Protocol (IP) data, wherein the host unit includes:

a baseband unit configured to perform baseband processing to place IP data onto a channel, wherein the baseband unit is configured to convert between IP data and baseband, digital data; and

one or more interfaces configured to output one or more antenna data streams comprising the baseband, digital data; wherein the one or more interfaces are configured to output the one or more antenna data streams with destination information;

one or more remote units communicatively coupled to the host unit, where each remote unit of the one or more remote units is configured to convert the one or more antenna data streams to one or more RF signals.

22. The system of claim 21, wherein the baseband, digital data corresponds to data formatted for a common public radio interface (CPRI) based protocol.

23. The system of claim 21, wherein the one or more remote units includes a plurality of remote units.

24. The system of claim 23, wherein the host unit is configured to perform splitting and summing for simulcast.

25. The system of claim 21, wherein each remote unit of the one or more remote units is configured to transmit the one or more RF signals to mobile devices via an antenna.

26. The system of claim 21, wherein each remote unit of the one or more remote units is configured to transmit RF signals to mobile devices using multiple frequency bands.

27. The system of claim 21, wherein the host unit further comprises a user interface for alarm, status, or configuration management.

28. The system of claim 21, wherein the one or more remote units are communicatively coupled to the host unit with optical fiber.

29. The system of claim 21, wherein the one or more interfaces are configured to output the one or more antenna data streams as serial data streams.

30. A host unit comprising:

a baseband unit configured to receive Internet Protocol (IP) data, wherein the baseband unit is configured to perform baseband processing to place IP data onto a channel, wherein the baseband unit is configured to convert between IP data and baseband, digital data; and

one or more interfaces configured to output one or more antenna data streams, wherein the one or more antenna data streams comprise the baseband, digital data; wherein the one or more interfaces are configured to output the one or more antenna data streams with destination information.

31. The host unit of claim 30, wherein the baseband, digital data corresponds to data formatted for a common public radio interface (CPRI) based protocol.

32. The host unit of claim 30, wherein the one or more interfaces comprise one or more optical interfaces.

33. The host unit of claim 30, wherein the one or more interfaces includes a plurality of serial interfaces.

34. The host unit of claim 33, wherein the host unit is configured to perform splitting and summing for simulcast.

35. The host unit of claim 30, wherein the host unit further comprises a user interface for alarm, status, or configuration management.

36. The host unit of claim 30, wherein the one or more interfaces are configured to output the one or more antenna data streams as serial data streams.
